TUNNELING APPARATUS

Antonio D. Caputo, Pittsburgh, Pa.

Application June 14, 1939, Serial No. 279,111

8 Claims. (Cl. 61—85)

The invention relates to a sheet metal shield of arch form which is advanced into the tunnel as excavations progress, and which will support the earth while the permanent tunnel lining is being installed.

One object of my invention is to provide a tunnel shield structure or temporary roof and wall support of such form that it can conveniently be advanced as excavation progresses and which can be readily manipulated to direct it in curved paths.

Another object of my invention is to provide a tunnel shield and jack advancing means therefore, so arranged that they can conveniently be employed in facilitating the installation of the permanent lining for the tunnel.

Referring to the accompanying drawings, Figure 1 is a longitudinal sectional view of the apparatus; Fig. 2 is a protracted plan view of the tunnel shield and hood of Fig. 1; Fig. 3 is a sectional view on an enlarged scale through one of the lifting jacks of Fig. 1; Fig. 4 is a side view thereof; Fig. 5 is a view taken on the line V—V of Fig. 4; Fig. 6 is a view taken on the line VI—VI of Fig. 4; Fig. 7 is a longitudinal sectional view showing a modification of the structure of Fig. 1; Fig. 8 is a similar view showing means for distributing thrust stresses of the horizontal jacks to the permanent tunnel lining members; Fig. 9 is an enlarged detailed view showing the manner in which the hood portion of the shield is connected to the forward portion thereof, and Fig. 10 is a longitudinal sectional view showing a modification of the cutter blade of Fig. 1.

The apparatus comprises I-beams 12 and 13, each of generally arch form, connected by suitable cross bars 14 and 15, and constituting a frame for the shield plates. At each side of the frame a pair of jacks 16 support it on suitable track rails or plates 17. These jacks can be used to raise and lower the shield, and are mounted on trucks that comprise rollers which are journaled in housings 18 that shield the rollers from dirt and contain the bearings for the rollers.

As shown more clearly in Figs. 3 and 4, each jack comprises a screw 19 which is supported upon the truck and extends through a bracket 20 that is carried by the frame member 14 or the frame member 15, as the case may be, the screw 19 being splined or slidably keyed through its length, at 21 to the bearing bracket or block and an operating nut 22 being journaled in the block 20 and provided with radial holes whereby it may be turned by a bar or handle. Rotation of

the nut 22 will effect raising and lowering of the frame members 12 and 13.

The shield is divided into a front section A and a rear section B, the section A consisting of sheet metal plates 24 that are bolted or riveted to the frame members 12 and 13, the upper plates projecting forwardly of the arch beam 12 and carrying a blade 24a that serves as a cutting edge. The longitudinal edges of the plates 24 are connected by splice plates or bars 25 to which the plates are secured by screws or bolts.

The rear or hood section B of the shield is composed of sheet metal plates 27 whose forward edges are bolted to the arch beam 13. The abutting edges of the plates are connected by splice bars 28 disposed against the inner sides of the plates, and having countersunk holes through which screws 29 extend and have screw threaded engagement with holes in the plates 27. The heads of the screws will be flush with the inner surfaces of the bars 28. No permanent support other than the splice plates 28 are provided at the rear ends of the plates 27 and, therefore, the shield section B can flex somewhat in going around curves of large radius. When the shield is to be pushed around curves of short radius (either laterally or vertically), the screws 29 and the bars 28 will be removed, so that the plates 27 can flex more readily. For still further flexing of the plates 27, the bolts 30 (Fig. 9) at the forward ends of the plates will be loosened somewhat but not taken out, to provide some looseness or lost motion.

The shield A—B will be advanced by screw jacks 31, one of which will be mounted in the top of the shield and others at the sides thereof, interiorly of the shield. The jacks are supported by the arch bars 12 and 13 and are shown as extending through the web of the bar 13. At their rear ends they have thrust engagement with an arch bar 32 that constitutes part of the permanent tunnel structure or lining.

The jacks 31 each comprises a tubular portion 33 that is supported on the beams 12 and 13 and a screw 34 that has threaded engagement with the sleeve 33 and thrust engagement at its rear end with a beam 32. A worm gear 35 journaled in a bearing 39 in the web of the beam 13, is secured to the screw and is driven by a worm shaft 36 from an electric motor 37 that operates through reduction gearing indicated at 38, the motors being driven in a desired direction to effect expansion or retraction of the jacks. In order to advance the shield along a curved path, the jacks at one side thereof will be operated to

advance that side at a somewhat faster rate than at the other side.

The tunnel lining consists of a series of arch bars 32 to which filler plates 40 are connected, the edges of the plates being turned laterally to form flanges at their inner surfaces through which bolts or rivets are engaged to hold the plates together.

Before advancing the tunnel shield A—B from the position shown in Fig. 1, another arch bar 32 will be placed therein adjacent to the arch bar 13, as indicated by dotted lines in Fig. 1, and liner plates 40 put into position. Thereupon the shield will be advanced by the jacks 31.

15 Tar paper or other water proof material 41 can be placed around the outer sides of the beams 32 to prevent seepage of water through the tunnel lining. The paper will direct water to the floor of the tunnel at the edges of the lining, 20 from whence it can be drained or pumped away.

Where great force is required to advance the shield 23 by the jacks, heavy planks 42 will be placed between some of the arch bars 32 near the front of the permanent lining, and angle bars 25 43 will similarly be placed between said arch bars, as shown in Fig. 8. The angle bars 43 can readily be removed for further use. Thrust blocks or bars 44 which can suitably be of channel form may also be interposed between the rear 30 ends of the jack structures 34 and foremost beam 32, as shown more clearly in Fig. 8, to distribute pushing stresses thereon and thus prevent distortion thereof.

As indicated in Fig. 1, short planks 45 set within 35 arch beams 32, may be employed in lieu of the lining plates 40, or the upper portion of the lining may consist of metal plates 40 and the lower side portions thereof of the short planks 45.

Still another form of lining is shown in Fig. 40 7, such lining consisting of blocks or slabs 46 of reinforced concrete or the like, set into the I-beams 32 as shown, the blocks being mainly supported by these arch bars 32. To facilitate installation of the concrete blocks 46, the screw 34 45 will be retracted into the sleeve 33, whereupon the foremost arch bar 32 will first be placed in the hood 27 a little forwardly of its normal resting place, as shown at the upper right-hand corner of Fig. 7. Thereupon false work (not shown) 50 may be set into place for temporarily supporting the uppermost slabs 46, the rear ends of the slabs then being inserted into the next arch bar 32. When all of the slabs 46 have thus been placed, the foremost bar 32 will then be pushed backwardly by the jacks or otherwise, into interfitting 55 relationship with the front ends of the slabs 46. The jack screws 34 will then be brought into engagement with such foremost bar, to again advance the shield, as in Fig. 1.

60 In Fig. 10, I show a structure wherein a cutting edge or knife 47 can be adjusted longitudinally of the shield plates 24. When going through loose soil or sand which tends to "cave" too readily and thus interfere with operations 65 near the front end of the shield, as through loose material burying the trucks 18 and their jacks, the members 47 will be projected forwardly as indicated by the dark lines.

The blade or blades 47 are secured to an arched 70 plate or plates 48 that fit interiorly of the shield 24, and have slots 49 through which bolts extend to permit of said longitudinal adjustment. The flanged end 50 of the member and strengthening blocks 52 carried thereby, have threaded engagement with screws or jacks 51 that abut 75

against the arch bar 12, at 53. The screws 51 have heads 54 whereby the screws can be rotated by a wrench or in some other manner, to effect longitudinal adjustments of the cutter 47.

I claim as my invention:

1. Tunneling apparatus comprising a forwardly-projecting shield for penetrating and supporting the earth into which it is advanced, a hood section disposed rearwardly of the said shield and connected thereto, the said hood comprising 10 flexible plates extending longitudinally of the tunnel and curved to conform approximately to the cross sectional contour of the tunnel, and the longitudinal edges of adjacent plates being normally in abutting relation to one another.

2. Tunneling apparatus comprising a forwardly-projecting shield for penetrating and supporting earth as it is advanced, a hood section disposed rearwardly of the said shield and connected thereto, the said hood comprising flexible plates extending longitudinally of the tunnel and curved to conform approximately to the cross sectional contour of the tunnel, the longitudinal edges of adjacent plates being positioned adjacent to one another, and longitudinally-extending splice strips overlapping said adjacent edges.

3. Tunneling apparatus comprising a forwardly-projecting shield for penetrating and supporting earth as it is advanced, a hood section disposed rearwardly of the said shield and connected thereto, the said hood comprising flexible plates extending longitudinally of the tunnel and curved to conform approximately to the cross sectional contour of the tunnel, the longitudinal edges of adjacent plates being positioned adjacent to one another, and longitudinally-extending splice strips overlapping said adjacent edges and detachably secured to the inner faces of the plates, by attaching means that are countersunk with respect to the interior surface of the strips, whereby the strips may slide on permanent tunnel-lining bars placed within the said hood, when the shield is being moved forwardly.

4. Tunneling apparatus comprising a pair of laterally-spaced arch bars disposed crosswise of the tunnel, a shield mounted on said bars, a hood having its forward end supported by the rearmost bar and projecting rearwardly of the shield, and means for so connecting the forward end of the hood to the rearmost bar that the connection may be rigid when desired, or non-rigid, to provide a flexible joint between the hood and the shield.

5. Tunneling apparatus comprising a pair of laterally-spaced arch bars disposed crosswise of the tunnel, a shield mounted on said bars, a hood having its forward end connected to the rearmost bar and projecting rearwardly of the shield, and longitudinally-extending jacks carried by said bars and extending approximately to the rearmost edge of the hood, when expanded, the hood comprising flexible plates curved to conform approximately to the cross sectional contour of the tunnel, and the longitudinal edges of adjacent plates being positioned in abutting relation to one another.

6. Tunneling apparatus comprising a pair of laterally-spaced arch bars disposed crosswise of the tunnel, a shield mounted on said bars, a hood having its forward end connected to the rearmost bar and projecting rearwardly of the shield, longitudinally-extending jacks carried by

said bars and extending approximately to the rearmost edge of the hood, when expanded, and an arch bar fitting within said hood and engageable by the rear ends of the jacks, for supporting tunnel lining members, the shield and the hood being advanced when the jacks are expanded against the last-named arch bar.

5. Tunneling apparatus comprising a pair of laterally-spaced arch bars disposed crosswise of the tunnel, a shield mounted on said bars, a hood having its forward end connected to the rearmost bar and projecting rearwardly of the shield, longitudinally-extending jacks carried by said bars and extending approximately to the rearmost edge of the hood when expanded, and an arch bar fitting within said hood and engageable by the rear ends of the jacks, for supporting tunnel lining members, the shield and the hood being advanced when the jacks are expanded

against the last-named arch bar, and the hood being slidable on the said arch bar.

8. Tunneling apparatus comprising a pair of laterally-spaced arch bars disposed crosswise of the tunnel, a shield mounted on said bars, a hood having its forward end connected to the rearmost bar and projecting rearwardly of the shield, and longitudinally-extending jacks carried by said bars and extending approximately to the rearmost edge of the hood when expanded, the hood comprising flexible plates curved to conform approximately to the cross sectional contour of the tunnel, and the longitudinal edges of adjacent plates being positioned in abutting relation to one another, the said shield having a cutting edge projecting forwardly of the front arch bar.

ANTONIO D. CAPUTO.
